UNITED STATES PATENT OFFICE.

HAROLD A. SOULIS AND WILBUR T. SOULIS, OF NEW YORK, N. Y.

SHOCK-ABSORBING APPARATUS.

1,331,537.

Specification of Letters Patent. Patented Feb. 24, 1920.

Application filed April 1, 1915. Serial No. 18,506.

To all whom it may concern:

Be it known that we, HAROLD A. SOULIS and WILBUR T. SOULIS, citizens of the United States, and residents of New York, county of New York, and State of New York, have invented a new and useful Improvement in Shock-Absorbing Apparatus, of which the following is a specification, the principle of the invention being herein explained and the best mode in which we have contemplated applying that principle so as to distinguish it from other inventions.

The present improvements relate in general to mechanism for receiving severe shocks and recoils and more particularly to a device of the type popularly known as shock absorbers for use between the axles and frame of vehicles for assisting the springs to withstand severe jolts. The devices now used for that purpose are deficient in one particular which is that the resistance they offer is proportional to, and in fact is controlled by the relative movement between axle and frame. They continually dampen the spring action therefore and prevent the springs from absorbing the gentler jars in the proper manner since they stiffen the springs at all times. This action is not the best and our present device has been designed to proportion the resistance offered to the intensity of the shock and not to the distance through which the axle has moved toward or away from the frame. In this way the springs are given added resistance only when it is required and this increased resistance is proportioned to suit each individual shock, which obviously is the proper action for such a device. To the accomplishment of the foregoing and related ends, said invention, then, consists of the means hereinafter fully described and particularly pointed out in claims.

The annexed drawings and the following description set forth in detail certain mechanism embodying the invention, such disclosed means constituting, however, but one of various mechanical forms in which the principle of the invention may be used.

In said annexed drawings:—

Figure 1 is a side elevation of the preferred form of our device, the view being also partially sectioned, the plane of the section being indicated by the line 1—1 in Fig. 3; Fig. 2 is a side elevation illustrating the device as applied to one type of spring

on a vehicle; Fig. 3 is a section on the line 3—3 in Fig. 1; Fig. 4 is a section of a modified form of the device; and Fig. 5 is another sectional view illustrating a still different form of the invention.

Referring to the device illustrated in Figs. 1, 2 and 3, it will be seen that the device comprises two arms 1 and 2, which will be attached to the frame 3 and axle 4 of the vehicle respectively, as is usual with such devices. The precise attachments between the shock absorber and the axle and frame are immaterial so long as they have suitable connections therewith. These movable elements 1 and 2 are connected together by means of the pivoted block or pin 5, and thus have relative movement toward and away from each other when a shock is received in the axle 4 of the vehicle, tending to move the latter toward the frame 3.

The upper of the two arms 1, consists of two parts, the outer of which is the arm proper which is pivotally attached to a plate 6, and it is to this plate that the arm 2 is connected. It is immaterial whether the arm 1, consists of one or more members attached together, but as illustrated in Fig. 3, there are preferably duplicate arms 1, provided at their inner ends with cams 7 which are in contact with a rebent spring 8 pressing against an arcuate plate or shoe 9, which is carried by the plate 6 and bears against a correspondingly formed shoe 10 attached to the lower arm 2. The two arms are spaced apart by a bushing 37 shaped like the cams and mounted on the pin 16 and held in place by a small pin 38.

The arms 1 are maintained at a given distance from the pin 5 by means of external rods 12 adjustably engaging the same, while the spring 8 is maintained in position by having its ends passed through apertures 13 formed in the side members 15 which constitute the plate or member 6. The position of the cams 7 with respect to the plate 100 9 determines the pressure with which the spring 8 presses against the latter, and this may be initially adjusted by tightening or loosening the nuts 20 on the rods 12. If preferred, the two shoes 9 and 10 which operate as frictional members, may be formed of a suitable friction material in order to increase the resistance to relative movement between the same.

Initially, the resistance offered by the 110

pressure between shoes 9 and 10 is greater than the resistance offered by the spring 8 to oscillation of the cams 7. When a shock is first received, the arms 1 and 2 are moved 5 toward each other, and this pressure which we will assume is transmitted first to the arm 1, causes the latter to initially rotate about its axis, which is the pin 16. Accordingly the initial movement of the arm 1 produces a camming action against the rebent 10 spring 8, thus increasing the pressure of this spring against the plate 9, and in turn increasing the resistance offered by the friction between the plates 9 and 10 to the movement 15 of the plate 6 with respect to the arm 2. The cams 7 are so formed that the resistance offered to pivotal movement of the arm 1 by the spring 8, increases faster and more quickly than the increase in the resistance offered by the plates 9 and 10 to the movement 20 of the plate 6 about the pin 5, and accordingly after a certain movement by the arm 1, the arms 1 and 6 will turn as a unit about the pin 5. In order to turn these two 25 arms as a unit about the pin 5, a much greater pressure is required than to initially turn the arm 1 about the pivot 16, and in this way a graduated pressure is provided which will slowly and increasingly resist 30 movement between the frame and the axle. It will be obvious that any desired latitude of initial movement by the arm 1 can be secured by varying the form of the cams 7, and in this way changing the point in the 35 angular movement of the arm 1 at which the cam increases the pressure between the plates 9 and 10 to a point where the arms 1 and 6 will operate as a unit.

By the foregoing construction we secure 40 a shock-absorbing action which very closely approximates the theoretically perfect action for such a device. This is obtained not so much because of the increased resistance as by the way in which this increased resistance 45 acts and the conditions under which it becomes available. It will be apparent that the intensity of the jolt determines the initial speed of movement of the arm 1. The speed of movement of the arm determines the angle through which it will swing before being forced to swing as a unit with the plate 6. Thus a very heavy jolt will swing the arm 1 through a greater angle than a light jar. This results in varying the final resistance offered to swinging of arms 1 and 6 together, 50 since the pressure between the shoes 9 and 10 is determined by the amount of angular movement of the cams 7 on arm 1. The final resistance is a constant one, varying in direct proportion to the intensity of the jolt so that a light jolt produces very little resistance in the shock absorber and permits the springs to practically alone absorb the jars. In other words, the present device 55 presents no fixed resistance to movement but

a varying resistance varying with, and controlled by, the intensity of the shock. In this way the device is a proper auxiliary to a spring and not a damper on the same, and permits springs to be designed to accommodate the weaker shocks without being built up and stiffened to also meet the heaviest jolts. 7/

In Fig. 4, we have shown a modification of the invention in which there are also two 71 relatively movably connected arms 21 and 22. The arm 22 is formed at the connected end with a cylinder or circular plate 23 within which there are two spaced and diametrically opposed shoes or friction members 24. These friction members 24 are provided with transverse resilient plates 25 between which there is mounted a square cam 26 attached to the arm 21. Spacers 27 maintain the springs in the positions shown, these 80 spacers being unattached and floating within the drum 23. Initial movement of the arm 21 causes a camming action by the square cam 26 against the springs 25, thus increasing the pressure of the shoes 24 85 against the cylinder 23. After the arm 21 has moved through a predetermined arc, the resistance offered to further rotation of the cam 26 by the springs 25 is so great that the shoes 24 will turn as a unit with the arm 95 21, and, of course, as the result of the camming action against the springs 25, the pressure between the shoes 24 and the cylinder 23 will then very greatly increase, and therefore the resistance to relative movement between the two arms will be correspondingly increased. 100

In Fig. 5 we show a vertical construction comprising arms 30 attached to the frame and connected to cam 31 which are pivoted on a plate 32 and operate against resilient members 33 pressing against the outer of three spaced shoes 34. Between these shoes are other shoes 35 attached to the vehicle axle. The shoes 34 and 35 correspond in 105 function to the brake shoes in the preceding types. Upon initial movement the cams 31 press the members 33 against the friction shoes 34 and 35 thus increasing this pressure. Thus when the shoes finally move 110 with respect to each other the pressure between them has been much increased. The action is thus similar to that of the other types shown in the other figures. 115

The advantage of proportioning the resistance of the shock absorber to the intensity of the jolt will be apparent to all those skilled in the art. The springs are permitted to retain their full control over all smaller jars which is to be desired, as a 120 shock absorber merely resists, while a spring gives and returns, thus absorbing the energy in easy motion instead of merely stopping the motion as does the usual shock-absorber. On the other hand our device does act when 125 130

necessary to take up a heavy shock and acts with a force dependent on the intensity of the shock, so that the springs are supplemented in a way which will permit of their being designed to give the maximum ease of riding, which can only be done when the necessity for withstanding the heaviest jolts is eliminated.

It will be readily seen that the operation 10 of the device will be similar whether the movement is up or down. In either case the elements will coöperate to proportion the resistance to intensity of the shock, which is what is desired in such a device to 15 enable it to assist, and not hamper, the springs.

Other modes of applying the principle of our invention may be employed instead of the one explained, change being made as regards the mechanism herein disclosed, provided the means stated by any of the following claims or the equivalent of such stated means be employed.

We therefore particularly point out and 25 distinctly claim as our invention:—

1. In shock absorbing apparatus the combination of two relatively movable, connected elements; friction means carried by said elements and tending to resist relative movement of the same; resilient means adapted to cause initial pressure in said friction means; and other means operable by the initial relative movement and adapted to operate said resilient means to increase 35 the pressure of said friction means in direct proportion to the velocity of such initial relative movement of said elements.

2. In shock absorbing apparatus the combination of two relatively movable, connected elements, friction members mounted on said elements and adapted to contact thereby tending to resist relative movement, adjustable resilient means adapted to place said friction members under pressure to 40 vary their resistance to movement, and means operable by initial movement of said members and adapted to operate said resilient means to automatically increase the pressure thereof, the increase being directly 45 proportional to the velocity of the initial relative movement of said elements.

3. In shock absorbing apparatus, the combination of two relatively movable connected elements, friction means carried by said elements and tending to resist relative movement of the same, resilient means adapted to cause initial pressure in said friction means, and cam means mounted on one element and operable upon initial relative 50 movement to engage with said resilient means to increase the pressure in said friction means in direct proportion to the velocity of such initial relative movement of said elements.

4. In shock absorbing apparatus, the com-

bination of two relatively movable connected elements, friction means carried by said elements and tending to resist relative movement of the same, adjustable resilient means adapted to cause initial pressure in said friction means, means for varying the initial pressure of said resilient means, and a cam block mounted in one of said elements in engagement with said resilient means, said cam being operable upon initial relative 70 movement of said elements to increase the pressure exerted by said resilient means in direct proportion to the velocity of such initial relative movement of said elements.

5. In a shock-absorbing apparatus the combination of an arm provided with a friction member; a second arm pivotally connected to said first arm and having a complementary friction member adapted to contact with said first friction member; a spring 80 mounted on said second arm and being adapted to exert pressure upon said friction members; and a third arm pivotally connected to said second arm and adapted to contact with said spring upon movement of 90 said third arm and thereby increase the pressure of said spring upon said friction members.

6. In a shock-absorbing apparatus the combination of an arm provided with a friction member; a second arm pivotally connected to said first arm and having a complementary friction member adapted to contact with said first friction member; a spring 95 mounted on said second arm and being adapted to exert pressure upon said friction members; a third arm pivotally mounted in said second arm; a cam head mounted on said third arm and adapted to contact said spring upon movement of said third 105 arm, thereby increasing the pressure exerted by said spring upon said friction members.

7. In a shock-absorbing apparatus the combination of an arm provided with a 110 friction member; two side plates pivotally connected to said arm and having a complementary friction member adapted to contact with said first friction member; a spring mounted on said plates and adapted to place 115 said friction members under pressure; means for varying such spring pressure; a second arm pivotally mounted in said side plates and adapted upon movement about its axis to contact said spring, thereby increasing 120 the pressure exerted by the same on said friction members.

8. In a shock-absorbing apparatus the combination of an arm provided with a friction member; two side plates pivotally connected to said arm and having a complementary friction member adapted to contact with said first friction member; a spring 125 mounted on said plates and adapted to place said friction members under pressure; means 130

for varying such spring pressure; a second arm pivotally mounted in said side plates; and a cam head attached to said arm and adapted to contact said spring, movement of
5 said arm about its axis being adapted to increase the pressure on said spring and thereby on said friction members.

Signed by us this 26th day of March, 1915.
